BOTTLE CAP OR JAR COVER REMOVER

Roscoe A. Mitchell, Evansville, Ind.

Application September 2, 1943, Serial No. 500,969

3 Claims. (Cl. 81—3.46)

1

This invention relates to a bottle cap or jar closure remover, and aims to provide a device of this character wherein a direct upward pull will be directed to one edge of a bottle cap or can closure to remove the same, upon downward pressure being directed to the operating lever of the tool.

Another important object of the invention is to provide an opener of this character wherein a downward pressure in a direct line, will be directed to one edge of the cap, to insure against the breaking or distortion of the bottle or can from which the cover is being removed, during the operation of the tool.

Still another object of the invention is to provide a cap or cover remover which will be readily and easily adjusted, eliminating the necessity of operating adjusting screws or bolts to accomplish the adjustment.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawings:

Figure 1 is an elevational view of a can top or cover remover.

Figure 2 is a sectional view taken on line 2—2 of Fig. 1.

Figure 3 is an elevational view of a modified form of the invention especially designed for use in removing crimped bottle caps.

Figure 4 is a sectional view taken on line 4—4 of Fig. 3.

Figure 5 is a fragmental end elevational view of the bottle cap remover.

Figure 6 is a sectional view taken substantially on line 6—6 of Fig. 3.

Referring to the drawings in detail the body portion of the tool, is indicated generally by the reference character 5 and comprises a pair of members connected by means of the rivets 6, the rivets 6 also acting as spacers to maintain the members of which the body portion is constructed, in proper spaced relation with respect to each other.

The upper ends of the members are tapered as at 7 to be extended into the handle 8.

Slidably mounted between the members of the body portion 5, at a point adjacent to the lower end of the body portion, is a lifting arm 9 which

is formed with an elongated opening 10 that accommodates the pivot pin 11, whereby the arm is pivotally and slidably mounted with respect to the body portion. One end of the lifting arm 9 extends downwardly and is notched providing a lip 12 adapted to extend under the annular flange of the usual can closure that is held in position on a can by frictional contact therewith. The opposite end of the lifting arm 9 is formed into a handle 13 so that the arm may be readily and easily manipulated to properly adjust the arm and jaw, for various sized caps or covers. The upper edge of the lifting arm 9 is formed with teeth 14, for purposes to be hereinafter more fully described. It might be further stated that the lower end of the body portion 5 is substantially wide, and has a depending lip 15 providing a shoulder at its point of connection with the body portion, the shoulder and lip being designed to fit over one edge and the upper surface of the cap which is to be removed.

The operating handle of the tool is indicated by the reference character 16 and is formed at one end of the pressure lever 18 that is pivotally mounted between the members of the body portion, at 17, the forward end of the lever 18 being extended downwardly and rearwardly, where it has pivotal connection with the link 19 that in turn has pivotal connection with the link 20 which is also pivotally mounted between the members of the body portion. Pivotally connected to one end of the link 20, is an arm 21 which is formed with an opening to accommodate the lifting arm 9, the opening being appreciably wider than the width of the lifting arm 9, to permit of free movement of the lifting arm 9 within the opening to permit the adjustment of the lifting arm 9 to be made with facility.

Teeth 22 are provided along one end of the opening of the arm 21, the teeth being designed to engage teeth 14 of the arm 9 to prevent slipping of the arm 21, when the operating handle is forced downwardly during the cap-removing operation.

A coiled spring indicated at 23 has one of its ends connected to the link 20 at a point beyond the pivot point of the link 20, the opposite end of the coiled spring being secured to the body portion 5. This spring will act to return the arm 21 and handle 16 to their normal positions after they have been operated to lift the can cover from the can.

Secured to the forward end of the arm 9, adjacent to the lip 12, is a blade 24 and a guide finger 25 which is offset with respect to the blade,

the guide finger being disposed directly above the blade and spaced therefrom, so that the blade may be used in cutting the usual can top from a can, thereby providing a can-opening tool capable of removing various types of can closures.

In the form of the invention as shown by Fig. 3 of the drawings, the body portion of the opener is indicated by the reference character 26 and also embodies a pair of connected members formed with cut-out portions which, when the members are secured together, provide an opening for the arm 27 which is formed with an elongated opening 28 that accommodates the pivot pin 29 that is supported on the body portion, and extends across the opening. Thus it will be seen that due to this construction, the arm 27 may be moved forwardly, and then returned to the position as shown by Figs. 3, whereby the leverage will be appreciably increased.

The body portion is formed with a wide curved lip 29' which is adapted to fit over one edge of a bottle cap, the lip being of a length to extend to the usual bead of a bottle, directly under the cap, as shown by Fig. 3. Teeth 30 are formed directly above the lip 29' and are adapted to bite into the bottle cap to prevent slipping of the tool, when pressure is directed to the arm 27 in removing the cap.

The body portion is also formed with a depending finger 31 which has a rearwardly curved cap-engaging portion 32 adapted to fit directly under one edge of the cap being removed.

A chain indicated at 33', has connection with the body portion 26, near the upper end thereof, the opposite end of the chain being secured to the arm 27, by means of the collar 33. By adjusting the arm 27 with respect to the body portion, various degrees of leverage may be provided.

Secured to the depending finger 31 of the body portion, is a blade 34 and a guide finger 35 directly thereabove, whereby the device may be used for cutting out the top of the ordinary can, to open the can.

The cap-engaging portion 32 is formed with a plurality of substantially triangular lugs 36 of sizes to fit within the recesses or openings formed by the crimping machine in crimping the bottle cap in position. A corkscrew indicated at 37 is pivotally mounted on the arm 27. In operation, these lugs 36 will operate to prevent twisting of the cap to break the bottle, when excessive pressure is directed to the tool in removing the cap.

From the foregoing it will be seen that due to the construction shown and described, the arm 9 may be adjusted with respect to the body portion 5, to adapt the device for use in removing caps of various sizes. It will also be seen that because of this adjustment of the arm 9, the maximum leverage may be attained at all times, regardless of the size of cap being removed.

As the operating handle 16 of the device is forced downwardly, it will be obvious that a downward pressure will be directed to the arm 21 which in turn will cooperate with the teeth

14 of the lifting arm 9 to grip the latter arm and move same downwardly. This downward pressure forces the body portion into close engagement with one edge of the cap, while the lip 12 moves upwardly under the cap, prying the cap from its position on the jar or bottle on which it is located.

What is claimed is:

1. A jar cap remover comprising a body portion, one end of the body portion adapted to rest on a jar cap, a transversely disposed lifting arm pivotally connected with the body portion, one end of said lifting arm adapted to engage under a jar cap to be removed, a substantially vertical arm having an elongated opening through which the lifting arm extends, a link pivotally connected with the body portion and to which the substantially vertical arm is pivotally connected, a pressure arm pivotally mounted on the body portion, a link connecting said pressure arm and the link connected with the substantially vertical arm, whereby pressure directed to the pressure arm operates to lift the cap-engaging end of the horizontal arm, and a coiled spring connected with the body portion and pivoted link, said spring adapted to normally pull the vertical arm upwardly.

2. A jar cap remover comprising a vertical body portion, one end of the body portion adapted to rest on a jar cap, a lifting arm having an elongated opening, a pin extending from the body portion and being fitted in the elongated opening adjustably connecting the body portion and lifting arm, a cap-engaging lift formed on one end of the lifting arm, said lifting arm having teeth formed along the upper edge thereof, an arm having an opening through which the lifting arm extends and having teeth adapted to engage the teeth of the lifting arm adjustably connecting the lifting arm and arm through which the lifting arm extends, a pressure arm pivotally connected with the body portion, and links connecting the pressure arm and arm through which the lifting arm extends, whereby the cap-engaging end of the lifting arm is elevated when the pressure arm is forced downwardly.

3. A jar cap remover comprising a vertical body portion, a handle formed at the upper end 50 of the body portion, the lower end of the body portion adapted to rest on a jar cap being removed, a lifting arm having a lip at one of its ends, adapted to fit under the cap, means for pivotally connecting the lifting arm to the body portion, a pressure arm pivotally connected with the body portion below the handle thereof, and means for exerting downward pressure on one end of the lifting arm, lifting the cap-engaging end thereof, said means embodying an arm adjustable along the lifting arm and pivoted links connecting the pressure arm and last mentioned arm.
